United States Patent

Des. 236,669
Patented Sept. 9, 1975

236,669

OUTDOOR BENCH

Frank D. Macy, Canby, Oreg., assignor to
Tran-Sit Bench Systems Incorporated

Filed Sept. 4, 1973, Ser. No. 394,379

Term of patent 14 years

Int. Cl. D6—01

U.S. Cl. D6—59

FIG. 1

FIG. 2

FIG. 3

FIG. 4

FIG. 5

FIG. 1 is a front perspective view of an outdoor bench showing my design;

FIG. 2 is a front elevation thereof;

FIG. 3 is a top plan view thereof;

FIG. 4 is a bottom plan view thereof; and

FIG. 5 is a side elevational view of the bench on an enlarged scale taken from the right-hand side of FIG. 2.

I claim:

The ornamental design for an outdoor bench, as shown.
